Primary Examiner — Darlington Ly(74) *Attorney, Agent, or Firm* — Fox Rothschild LLP(57) **CLAIM**

The ornamental design for a motor truck cab wall panel, as shown and described.

DESCRIPTION

FIG. 1 is a right side elevation view of a motor truck cab wall panel embodying my new design;

FIG. 2 is a left side elevation view thereof;

FIG. 3 is a right side perspective view thereof;

FIG. 4 is a front and right side perspective view thereof;

FIG. 5 is a front elevation view thereof;

FIG. 6 is a rear elevation view thereof;

FIG. 7 is a bottom and left side perspective view thereof;

FIG. 8 is a bottom and right side perspective view thereof; and,

FIG. 9 is a right perspective view thereof in the context of a motor truck.

The broken lines and ghosted or low contrasted showings of the motor truck interior are provided for the purpose of illustrating environmental structure and form no part of the claimed design.
